UNITED STATES PATENT OFFICE

ADOLPH POTDEVIN, OF GARDEN CITY, NEW YORK, ASSIGNOR TO POTDEVIN MACHINE COMPANY, OF BROOKLYN, NEW YORK, A CORPORATION OF NEW YORK

BAG MAKING MACHINE

Application filed April 4, 1931. Serial No. 527,685.

This invention relates to apparatus for use in connection with the making of paper bags and is primarily directed to an apparatus for punching holes through the bag for the reception of the cord which in certain types of paper bags is employed as a handle.

The invention also provides a construction for cutting through the walls of the bag to provide for the insertion of stiffening material such as cardboard in the top of the bag.

A further object of my invention is the provision of apparatus for the purposes above described which are made adjustable so that the various parts can be adjusted relatively to each other and so that the parts may be adjusted to accommodate the machines to bags of different sizes.

In the drawings:

20 Fig. 1 is a section on the line 1—1 of Fig. 4;

Fig. 2 is a part sectional elevational view of a detail of the punch and die mechanism of Fig. 1;

25 Fig. 2A is a section on line 2A—2A of Fig. 2;

Fig. 3 is a section on the line 3—3 of Fig. 4;

Fig. 4 is an elevational view of the machine;

30 Fig. 5 is a perspective of one type of bag produced by this machine;

Fig. 6 is another view of the bag of Fig. 5;

Fig. 7 is a view of another type of bag produced by this machine; and

35 Fig. 8 is another view of the bag of Fig. 7.

Before going into a description of the machine or apparatus of this invention, I shall refer to Figs. 5, 6, 7 and 8 of the drawings of the bag itself.

40 The bag shown in Figs. 5 and 6 is punched through both walls thereof as shown at 4 and 5 and is creased transversely between the outer row of holes 4 and 5 and the next adjacent row as shown at 6.

45 In its completed condition a cord 7 is passed through the holes 4 and 5 in the manner indicated in Fig. 6, the top edge of the bag having just been folded inwardly along the crease 6, as also seen in Fig. 6.

50 Referring to the bag of Figs. 7 and 8, it

will be seen that this bag also is provided with holes 4 and 5 punched through both walls thereof. This bag likewise is creased at 8, 9 and 10 and is cut through as shown at 11 with a curved cut. It is to be noted 55 that the creases 8 and 9 and the creases 9 and 10 do not meet so as not to weaken the paper at the ends of the curved cut 11. This bag has its outer edges folded inwardly, as shown in Fig. 8, along the creases 8, 9 and 10 and 60 cord 12. The cord 12 is threaded therethrough as shown in Fig. 8, the curved cut 11 after the edges of the bag have been folded in permitting of the insertion of a cardboard or other suitable stiffening material 13. 65

The locations of the holes 4 and 5 in the two bags of Figs. 5 and 8 are the same or may be the same and this permits of the use of the same punching mechanism for punching these holes. However, when the bag is to be 70 finished as in Figs. 7 and 8 a different type of creasing mechanism is necessary so far as the creaser blade is concerned, three blades being employed in place of a single blade which will produce the crease 6 and it is necessary 75 to produce cutting mechanism for making the curved cut 11, which mechanism is not used when operating on the bag of Fig. 5.

It will be appreciated, therefore, that the same apparatus is employed for certain of the 80 operations to be performed at all times, while additional apparatus is necessary when shifting from the type of bag shown in Fig. 5 to that shown in Fig. 7, for instance.

Accordingly I have shown in the drawings 85 of the apparatus all of the mechanism required for both types of operation, it being appreciated, as will be brought out herein-after, that only a part of this apparatus is employed in each instance.

90 Referring to the drawings of the machine, it will be seen that 14 and 15 designate two shafts in alignment with each other and arranged in superimposed relation.

95 On the upper shaft 14 are a series of discs designated 16, 17, 18, 19, 20 and 21. These discs are all provided with a collar equipped with a set screw designated s by which the discs are held to the shaft and by which the discs are adjustably held to the shaft 14, this 100

arrangement permitting of the adjustment of all of these discs about the axis of the shaft 14.

On the lower shaft 15 are a series of discs 22, 23, a pair of discs 24, 25, another pair of discs 26, 27 and discs 28, 29. As will be seen from the drawings discs 22 and 23 immediately underlie discs 16 and 17 and discs 28 and 29 immediately underlie discs or rollers 20 and 21. These discs are all adjustably held to the shaft 15 by set screws 30 whereby the discs are adjustable about the axis of the shaft.

The discs 18 and 19 on the upper shaft 14 are equipped with punches shown in detail in Figs. 1 and 2 and indicated in Fig. 4.

As will be seen from Fig. 1, the face of each of the discs 18 and 19 is provided with a series of holes 31 spaced circumferentially of the disc. These holes are for the reception of bolts 32 by which brackets 33 are adjustably attached to the faces of the discs. Provision of a plurality of holes 31 permits of coarse adjustment or setting of the brackets 33 while for a finer adjustment the brackets are provided with a cylinder 34 which receives the bolts 32 already referred to.

I have shown three sets of the brackets 33 for purposes of illustration, it being appreciated of course that this number can be varied as desired. Each of the brackets carries a punch 35 equipped as shown in Fig. 2 with an ejector 36 which may be in the form of a rubber sleeve, for instance. Each one of the punches 35 is adjustable endwise in the bracket and is held in adjusted position by a set screw 37.

The punch is carried in a block 38 which permits of lateral adjustment of the punch, the block being carried in a slot 39 and secured in position by a bolt 40.

It will be appreciated from the description thus far given that the punches 35 may be adjusted into any position desired due to the adjustable mounting of the discs 18 and 19 on the shafts 14, the adjustability of the brackets 33 on these discs and the adjustability of the punches in the brackets. This gives great flexibility to the machine and permits it to be adjusted to accommodate bags of many different sizes.

The dies which are provided for cooperation with the punches 33 are carried by the lower discs 24, 25 and 26, 27.

Referring to Fig. 1 it will be seen that the face of the disc 25 adjacent the companion disc 24 is provided with a circumferential groove 41, the inner face of disc 24 being provided with a similar groove. In these grooves are die blocks 42, it being appreciated that there will be a die block for each of the punches 35. The discs are clamped together by bolts 43 so as to clamp the die blocks. This construction permits of the die blocks being shifted circumferentially of the discs so as to

bring them into proper register with the punches 35. It is to be understood of course that the discs 26 and 27 are similarly constructed.

Extending across the discs 16, 17, 18, 19, 20 and 21 is a creaser bar 44 which is set into a slot provided in the faces of the discs 16, 17, 20 and 21. One or more of the discs may be provided with a counter-sunk hole 45 through which a set screw 46 is entered and screwed against the side of the creaser bar to hold the same in position and incidentally permit its removal when necessary. The bar 44 is provided with a creaser blade 47.

Extending across the lower discs 22, 23, 24, 25, 26, 27, 28 and 29 is a block 48 set into the discs and provided on its outer surface with a groove 49 extending lengthwise thereof.

It will be seen from Fig. 1, for instance, that the creaser blade 47 is intermediate the two punches 35 which punch two sets of holes 4 and 5 at the outer end of the bag so that the crease will lie in the position of the crease 6 of Fig. 5 intermediate these two sets of holes.

In operation the punches 35 are set in their desired relative positions, the die blocks 42 being correspondingly set and the bags run through the machine to punch the holes 4 and 5 and on the same passage of the bag creasing the bag at 6.

This apparatus is for punching the holes and creasing the bag as illustrated in Fig. 5.

When it is desired to punch the bag, crease it as indicated at 8, 9 and 10 and to cut the half-round cut 11 therein, as illustrated in Fig. 7, apparatus additional to that so far described is employed. This apparatus I have illustrated in Fig. 3 and it is also shown in Fig. 4.

Referring to these figures of the drawings, it will be seen that the upper shaft 14 intermediate the discs 18 and 19 is equipped with a member designated 50 clamped to the shaft 14 by bolts 51 so as to be adjustable on the shaft and so that this additional apparatus may be readily placed in position or removed from the machine entirely. This member 50 in part comprises an arm 52 extending radially with respect to the shaft 14 and equipped at its outer end with a curved knife 53, this knife it will be understood being curved to the curvature of the cut 11 of Fig. 7.

The lower shaft 15 intermediate the discs 25 and 26 is equipped with a member 54 adjustably clamped to the shaft by bolts 55, this member being provided with an arm 56 extending outwardly from the shaft and provided on its outer end with a block 57. The surface 58 of this block cooperates with the knife 53. This block is also provided on its face with a groove 59 cooperating with a creaser blade 60 which is mounted in the outer end of the member 52 on the upper

shaft 14. It is to be noted that the creaser blade 60 is slightly shorter than the diameter of the knife 53 so that the creaser blade will crease the bag along the crease 9 of Fig. 7 intermediate the ends of the cut 11.

Extending across the faces of the discs 16 and 17 and in line with the creaser bar 60 is a creaser block equipped with a creaser blade or bar 61, this blade terminating short of the end of the knife 53. The discs 20 and 21 are likewise equipped with a similar creaser bar 62 which terminates short of the other end of the knife 53.

The lower discs 22, 23 and 24 are equipped with a block 63, this block being provided with a groove 64 for cooperating with the bar 61. The discs 27, 28 and 29 are likewise equipped with a similar block 65 provided with a groove 66 for cooperation with the creaser bar 62.

When the apparatus just described is to be employed the creaser block 44 and its blade 47 are removed from the machine and creaser blocks 61 and 62 are placed in their respective grooves in the members 16, 17 and 20, 21. The members 50 and 54 are then applied to the shafts 14 and 15 and clamped in place thereon so as to bring the knife 53 into proper position with respect to the member 58. The punches 35 are also adjusted so as properly to locate these punches with respect to the knife 53. If a bag is now run through the machine the seam will be punched as shown at 4 and 5 in Fig. 7 and the creaser blades 61, 60 and 62 will crease the bag at 8, 9 and 10 as shown in Fig. 7 and the knife 53 will cut through the wall of the bag in a curved cut as shown at 11 in Fig. 7.

From all of the foregoing it will be appreciated that I have provided an apparatus suitable for operating on the bags of Figs. 5 and 7, in which the discs 18 and 19 and the equipment carried thereby and the discs 24, 25 and 26, 27 with their equipment are employed along with the creaser blade 47 in operating on the bag in Fig. 5.

It will be appreciated that when the bag of Fig. 7 is to be operated on then the creaser blade 47 is removed, the punches 35, however, being retained together with the die blocks 42 and the additional equipment shown in Fig. 3 placed in position, including the creaser blades 61, 60 and 62 and the cooperating blocks 63 and 64 and the member 58.

It will be appreciated, furthermore, that by the adjustability of the various devices employed in this apparatus the change from one type of operation to another type may be readily and accurately made.

It will be appreciated, furthermore, that this adjustability of the various parts of the apparatus enables the apparatus to handle bags of varying sizes and that the holes 4 and 5 may be varied in their positions both

longitudinally and transversely of the bag and with respect to each other as desired.

It will be appreciated that the location of the score on the bag can be varied as desired and that more than one crease may be provided if necessary.

What I claim is:—

1. In a bag making machine the combination of punches for punching holes through the walls of a bag tube, dies cooperating with said punches, rotary mounts for said punches and cooperating dies, said punches and dies being individually adjustable in said mounts circumferentially thereof, and said mounts being adjustable along their axes of rotation to obtain a variation in the position of the holes relatively to each other transversely as well as lengthwise of the bag.

2. In a bag making machine the combination of a pair of rotatable members, punches carried thereby for punching holes through the walls of a bag tube, cooperating dies, a pair of rotatable members carrying said dies, and means for adjusting said rotatable members lengthwise of their axes of rotation and said punches and dies circumferentially of said rotatable members to vary the relative position of the holes punched transversely as well as longitudinally of the bag tube.

3. In a bag making machine the combination of a rotatable disc, a plurality of brackets, the face of said disc being provided with a plurality of spaced holes, bolts passing through said brackets and into said holes whereby the brackets are adjustably secured to the face of said disc, each bracket being slotted for the reception of said securing bolts whereby a fine adjustment of the brackets circumferentially of the discs is obtained, a punch carried in each bracket, a mount for each punch whereby the punch can be adjusted parallel to the axis of rotation of the disc and also radially of the disc.

4. In a bag making machine the combination of a disc, a creaser blade on the periphery of said disc, and a plurality of punches carried on the face of said disc and adjustable circumferentially thereof with respect to said creaser blade.

5. In a bag making machine the combination of a disc carrying a punch, a cooperating die, a pair of discs clamped to each other for clamping said die, said punches and die being adjustable circumferentially of their respective discs.

6. In a bag making machine the combination of a rotatable disc, a punch carried thereby, said punch being adjustable circumferentially of said disc and said disc and punch being adjustable along the axis of rotation of said disc, a cooperating die, a pair of discs clamping said die, said die being adjustable circumferentially of the clamping discs and said clamping discs and die

being adjustable along the axis of rotation of the clamping discs.

7. In a bag making machine the combination of a pair of clamping discs, a punch die, 5 the adjacent faces of said discs being cut back to provide a groove for the reception of said punch die and permitting of said die being adjusted circumferentially of the clamping discs, said discs and die being adjustable along the axis of rotation of the discs, a second disc and a punch carried by 10 said second disc and cooperating with said die, said last mentioned disc being adjustable along the axis of rotation of the punch-car- 15 ryng disc and the punch being adjustable circumferentially of its carrying disc.

8. In a bag making machine the combination of a rotatable member, a shaft carrying the same and on which said member is adjustably mounted, a curved knife carried by 20 said member, punch carrying discs on said shaft at each side of said knife-carrying member, and rotatable dies at each side of said knife and cooperating with said punches.

- 25 9. In a bag making machine the combination of a rotatable shaft, a pair of spaced discs carried on said shaft, punches carried on said discs, a knife-carrying member on said shaft intermediate said discs, a second 30 shaft, discs carried thereby, dies cooperating with said punches carried by said last-mentioned discs, creaser blades at each side of said knife, and an intermediate creaser blade, said creaser blades being in alignment and 35 all of the creaser blades terminating short of the extremities of said knife.

This specification signed this 2 day of April, 1931.

ADOLPH POTDEVIN.
